CLAIM

The ornamental design for an office booth, as shown and described.

DESCRIPTION

FIG. 1 is a front right perspective view of an office booth.
FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines shown in the drawings illustrate portions of the office booth that form no part of the claimed design.
